UNITED STATES PATENT OFFICE

JOACHIM GIARDINO, OF WEST NEW YORK, NEW JERSEY

LET-OFF MECHANISM FOR NOVELTY FABRIC LOOMS

Application filed December 24, 1929. Serial No. 416,259.

This invention relates to let-off mechanisms for looms and particularly in the weaving of what are known as novelty fabrics, and particularly for velvet pile weaves of plain or fancy designs or a combination of plain and fancy designs; and the object of the invention is to provide a mechanism of the class specified which may be built into and constitute a part of a loom of conventional design, said mechanism having means for controlling and regulating the discharge of the warp threads and for regulating the tension of said threads as fed to the weaving machine in such manner as to compensate for both plain and fancy design fabrics; a further object being to provide means for intermittently feeding the warp threads from the warp beam, said means involving a friction roller and means for automatically stopping the feed of the warp thread when the slackening loop of said thread becomes relatively large; a further object being to provide means for straightening a cluster of warp threads prior to their transmission to the weaving machine; and with these and other objects in view, the invention consists in a mechanism of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a diagrammatic view illustrating the several parts of my improved mechanism and indicating the use thereof; and,

Fig. 2 is a detail plan view of a part of the construction shown in Fig. 1.

In the drawing I have indicated at 5 a frame which may be attached to or constitute a part of the framework of the weaving machine and supported in suitable bearings 6 in said frame is a transverse shaft 7 on which is mounted a friction drive drum 8 having a rubber or other friction facing 8a. To one end of the shaft 7 is attached a pick

wheel 9 inwardly of which is arranged a brake wheel 10 around which passes a strap or belt 11 attached to the frame 5 as seen at 12 and from the free end of which is supported a plurality of weights 13.

The frame 5 or the bearings 6 thereon include upwardly directed guide rails 14 upon which the projecting ends of a shaft 15 of a warp beam 16 is adapted to rest in supporting the warp threads 17 wound on said beam upon the surface of the friction drive drum 8 in the manner clearly seen in Fig. 1. Straps 18 are employed in conjunction with the guide rails 14 to prevent accidental displacement of the beam, and the upper ends of said rails are notched as seen at 19 to support the beam out of engagement with the drum 8 whenever desired.

Pivoted to a downwardly directed extension 20 on the frame 5 as seen at 21 is a lever 22 to the free end of which is connected a link 23 which also connects with the jack of the dobby of the weaving machine so that intermittent movement is transmitted to the lever to move a pawl 24 adjustably pivoted to the lever as seen at 25 and normally in engagement with the teeth of the pick wheel 9 to impart intermittent rotary movement to said wheel. The pawl 24 is normally held in engagement with the wheel 9 by means of a weight 26 adjustably supported on an arm 27 constituting part of the pawl 24. It will be understood that a relatively large number of threads are taken off from the beam and these threads may be handled singly or in multiple as may be desired.

In one use of the invention, the threads are passed over a bar 28 and then around cross rods 29 and over another bar 30 constituting part of a straightening device 31 which is held stationary in this particular use of the invention with the bar 30 arranged in the position seen in Fig. 1. The warp threads 17 extend from the bar 30 as seen at 17a to the weaving machine. This method of feeding the warp threads is designed primarily for use in the weaving of plain fabrics but when it is desired to weave what are termed novelty fabrics having predetermined designs arranged in the finished prod-

uct, the warp threads either singly or in clusters are passed through guide rings 32 to which rings are attached depending wires or strands 33 having weights 34 at the lower ends thereof.

5 After passing through the rings, the threads are then passed over rods 35 and 36 disposed at opposite sides of the shaft 37 of the straightening device 31. At one end 10 of the shaft 37 is a pulley 38 around which is passed a cord belt 39 which passes around another pulley 40 on a shaft 41 driven by or in operative connection with a rotatable shaft of the machine.

15 The straightening device is used primarily when clusters of warp threads are fed through each of the eyes 32, three of said clusters being indicated at 17b in Fig. 2 of the drawing. I have found that there is a 20 tendency to develop a twist in the clusters of threads and the device 31 and rods 35 and 36 operate to unravel the twisted threads to permit them to be fed separately to the machine as indicated at 17c in said figure.

25 The rotation of the device 31 which is in the direction of the arrow α , causes the twisted threads to be unraveled by virtue of the intermittent engagement of the rods 35 and 36 therewith which tend to constantly 30 feed back in the direction of the rings 32 the twisted portion of the threads. While a portion of the threads may be twisted intermediate the separate rods 35 and 36, the rod assuming the position shown to the right 35 of Fig. 1, will immediately take up and feed back the twisted threads as they are drawn through said straightening device and over said rods, it being understood that the rods rotate about the axis 37.

40 In the process of weaving, the separate threads or clusters of threads passed through the series of rings 32 which are provided, will be extended into loops of different depths, depending upon the particular type 45 of design being formed in the fabric, and when these loops become extended in the manner indicated in full lines in Fig. 1 of the drawing, the threads will engage a transverse bar 42 of a detector or automatic release device 43 secured to a rocker shaft 44 having an arm 45, the free end of which is 50 connected with the pawl 24 by means of a link 46.

55 When the threads engage the bar 42, the detector 43 is moved to the left to disengage the pawl 24 from the pick wheel and this operation is performed against the weight tension 26, thus stopping the feed of the warp threads from the beam 16 and allowing the threads to be drawn into the machine by raising the rings 32 against the tension of their weights 34 until such time as the detector has been released to again permit the pawl 24 to move into engagement with the pick wheel to permit the rotation there-

of. The detector above referred to prevents the undue extension of the loop formed in the thread and yet permits the formation of a slight loop therein without interfering with the feeding operation of the warp 70 thread and its discharge from the beam.

I also may use in conjunction with the warp beam 16 a creel warp 47 having a plurality of bobbins 48 from which warp threads 49 may be removed in single or 75 multiple as may be desired, said threads passing through a reed 50 and may extend around the cross rods 29 or through the rings 32 as may be desired. This creel warp is used primarily in producing fancy 80 designs where the take-up varies to an unlimited degree with respect to the separate end or group of ends of the warp. While the creel warp may be used independently, it may also be used in conjunction with the 85 warp 17 in producing some designs or forms in the resulting product.

It will be understood that various types and sizes of pick wheels may be employed in the mechanism, and to compensate for 90 the different size wheels, the pawl 24 is rendered adjustable with respect to the lever 22. The use of wheels of different sizes will govern the particular type of merchandise being woven, especially with respect to short 95 piles and higher piles.

It will be understood that while I have diagrammatically illustrated one form of mechanism for carrying my invention into effect, that I am not necessarily limited to the specific structural arrangement herein shown and described, and various changes 100 therein and modifications thereof may be made within the scope of the appended claims without departing from the spirit of my invention or sacrificing its advantages.

Having fully described my invention, what I claim as new and desire to secure by Letters Patent, is:

1. A let-off mechanism for weaving machines comprising a pick wheel, a friction feed drum rotatable by said wheel, a warp beam, means for supporting said beam to rest by gravity upon said drum, a lever in operative engagement with the jack of the 110 dobby of the machine, a pawl on said lever and normally in engagement with said wheel whereby in the movement of said lever, intermittent rotary movement is imparted to 115 said wheel and drum to discharge the warp threads from said beam, and tensional means engaging the threads fed from said warp beam.

2. A let-off mechanism for weaving machines comprising a pick wheel, a friction feed drum rotatable by said wheel, a warp beam, means for supporting said beam to rest by gravity upon said drum, a lever in operative engagement with the jack of the 125 dobby of the machine, a pawl on said lever 130 and normally in engagement with said wheel whereby in the movement of said lever, intermittent rotary movement is imparted to said wheel and drum to discharge the warp threads from said beam, and tensional means engaging the threads fed from said warp beam.

and normally in engagement with said wheel whereby in the movement of said lever, intermittent rotary movement is imparted to said wheel and drum to discharge the warp threads from said beam, tensional means engaging the threads fed from said warp beam, and said means comprising weighted rings through which the warp threads are adapted to pass to control and regulate the tension of said threads fed into the weaving machine.

3. A let-off mechanism for weaving machines comprising a pick wheel, a friction feed drum rotatable by said wheel, a warp beam, means for supporting said beam to rest by gravity upon said drum, a lever in operative engagement with the jack of the dobby of the machine, a pawl on said lever and normally in engagement with said wheel whereby in the movement of said lever, intermittent rotary movement is imparted to said wheel and drum to discharge the warp threads from said beam, tensional means engaging the threads fed from said warp beam, said means comprising weighted rings through which the warp threads are adapted to pass to control and regulate the tension of said threads fed into the weaving machine, and a straightening device interposed between said rings and the machine for unraveling twisted threads prior to their transmission into the machine.

4. A let-off mechanism for weaving machines comprising a pick wheel, a friction feed drum rotatable by said wheel, a warp beam, means for supporting said beam to rest by gravity upon said drum, a lever in operative engagement with the jack of the dobby of the machine, a pawl on said lever and normally in engagement with said wheel whereby in the movement of said lever, intermittent rotary movement is imparted to said wheel and drum to discharge the warp threads from said beam, tensional means engaging the threads fed from said warp beam, said means comprising weighted rings through which the warp threads are adapted to pass to control and regulate the tension of said threads fed into the weaving machine, a straightening device interposed between said rings and the machine for unraveling twisted threads prior to their transmission into the machine, said straightening device comprising spaced rods rotatable about a fixed axis, and means in operative connection with the machine for rotating said rods.

5. A let-off mechanism for weaving machines comprising a pick wheel, a friction feed drum rotatable by said wheel, a warp beam, means for supporting said beam to rest by gravity upon said drum, a lever in operative engagement with the jack of the dobby of the machine, a pawl on said lever and normally in engagement with said wheel

whereby in the movement of said lever, intermittent rotary movement is imparted to said wheel and drum to discharge the warp threads from said beam, tensional means engaging the threads fed from said warp beam, and a creel warp from which warp threads are adapted to be fed through said tensional means and into the machine.

6. A let-off mechanism for weaving machines comprising a pick wheel, a friction feed drum rotatable by said wheel, a warp beam, means for supporting said beam to rest by gravity upon said drum, a lever in operative engagement with the jack of the dobby of the machine, a pawl on said lever and normally in engagement with said wheel whereby in the movement of said lever, intermittent rotary movement is imparted to said wheel and drum to discharge the warp threads from said beam, tensional means engaging the threads fed from the warp beam to regulate the tension of said threads fed into the weaving machine, and means actuated by the warp threads when in predetermined position for moving and supporting said pawl in inoperative position to momentarily prevent rotation of said drum and beam.

In testimony that I claim the foregoing as my invention I have signed my name this 20th day of December, 1929.
